UNITED STATES PATENT OFFICE.

JOHN M. HANSEN, OF PITTSBURG, PENNSYLVANIA.

BOX OR PRODUCE CAR.

SPECIFICATION forming part of Letters Patent No. 727,620, dated May 12, 1903.

Application filed July 31, 1902. Serial No. 117,779. (No model.)

To all whom it may concern:

Be it known that I, JOHN M. HANSEN, a resident of Pittsburg, in the county of Allegheny and State of Pennsylvania, have invented a new and useful Improvement in Box or Produce Cars; and I do hereby declare the following to be a full, clear, and exact description thereof.

My invention relates to railway-cars, and more especially to box-cars having a metallic underframe and a wooden superstructure. Its object is to improve cars of this type in details of construction, which will be herein-after described and claimed.

15 In the accompanying drawings, Figure 1 is a view of one end of the car, a part being in section and the remainder being a plan of the underframe. Fig. 2 is a central vertical section through the lower portion of the same.

20 Fig. 3 is an end view of the car; and Fig. 4 is a vertical section on the line 4-4, Fig. 1.

The underframe of the car may be of any desired construction, that shown comprising center sills 1, side sills 2, draft-sills 3, body-

25 bolsters 4, and suitable connecting members. All of these parts may be of any desired construction and form no part of my invention. Therefore detailed description thereof is not deemed necessary. The superstructure also

30 may be of any preferred wooden construction, having the wooden floor 6 and wooden side and end walls 7.

My invention relates entirely to the end sill and hood construction, which is as follows:

35 The end sill 10 comprises a plate of angle shape having its web located in a vertical position, as shown, and having a flange 11 formed on its lower edge to stiffen the same. This flange is shown as turned inwardly; but, if desired, it may be turned outwardly, and, if desired, it may be formed by an angle-bar riveted to the plate. At its center the lower edge of the end sill is cut away to make room for the coupler-horn brace 11^a. This end sill

45 is reinforced by means of an angle-bar 12, having its vertical flange projecting upwardly and riveted to the inner face of said end sill and having its horizontal flange projecting inwardly, as shown, and serving as a support for the end wooden nailing-strip 14, which is suitably secured to the end sill. At the center of the car is a hood 15, secured to the end

sill in order to strengthen the same, said hood being formed of a steel plate pressed to shape and being provided with the upturned flange 55 17, by means of which it is riveted to the end sill. At its center the hood is provided with a notch for the passage of the draw-bar shank, and the sides of this notch, as well as the lower edges of the hood, are provided with inturned 60 flanges 18. Said hood embraces the ends of the draft-sills 3 and is secured thereto by having its inturned bottom flange riveted to said draft-sills. A draw-bar carrier 19, formed of a section of angle-iron, is supported from the 65 hood. The brace 11^a projects against the front wall of the hood and gives strength where the horn of the coupler strikes.

The end sill of the car is exceedingly simple and easy to make and, together with the 70 reinforcing-angle 12, forms a convenient means for supporting the wooden superstructure, while the hood strengthens the end sill and serves as a suitable means for connection to the ends of the draft-sills. 75

What I claim as my invention, and desire to secure by Letters Patent, is—

1. A metallic end sill for railway-cars, comprising an angle shape of uniform cross-section and a reinforcing-angle secured near the 80 upper edge thereof.

2. A metallic end sill comprising a plate provided with a flange on its lower edge, and a stiffening-angle having its vertical flange projecting upwardly secured to the inner face 85 near the upper edge of said end sill.

3. In a railway-car, the combination with a metallic end sill of angle shape having its flange projecting inwardly, and a hood formed of pressed steel provided with a vertical flange 90 riveted to the outer face of said end sill and having an opening for the passage of the draw-bar shank.

4. In a railway-car, the combination with an end sill of angle shape having its web arranged vertically and a horizontal flange at its lower edge and having a notch in its lower edge near the center, and a hood formed of pressed steel provided with a vertical flange for riveting to the end sill and provided with 100 an opening for the draw-bar shank.

5. In a railway-car, the combination with a metallic end sill, a hood formed of pressed steel provided with a vertical flange for riv-

eting to the end sill and having an opening for the draw-bar shank, and a coupler-horn brace secured in said hood and having its end bearing against the front wall of said 5 hood.

6. In a railway-car, the combination with an end sill having a notch in its lower edge near the center, a hood formed of pressed steel provided with a vertical flange for riv-
10 eting to the end sill and provided with an opening for the draw-bar shank, draft-sills

projecting through the notch in said end sill into said hood, and a coupler-horn brace se-
cured between said draft-sills and bearing against the front wall of said hood. 15

In testimony whereof I, the said JOHN M. HANSEN, have hereunto set my hand.

JOHN M. HANSEN.
